FLIGHT ATTACHMENT

Ernest C. C. Miller, Laurelton, N. Y.

Application January 25, 1949, Serial No. 72,715

4 Claims. (Cl. 198—175)

1

My invention relates to a flight attachment, and the invention may be said to be an improvement over the device described in Patent 2,313,259 to Carl C. Ottoson.

In the said patent there is described a flight attachment for flexibly mounting flights in a conveyor, as in the conveyor of a self-loading refuse truck. The flights are flexibly or resiliently mounted on the conveyor side chains, and the flight mountings are so arranged as to adequately protect the bearing parts, springs, etc. from mechanical injury or contamination by refuse and other foreign matter. In the said patent and in other prior-art devices employing resilient flight mountings, difficulties are experienced with spring breakage and in the replacement of springs.

It is, accordingly, an object to provide an improved resilient flight mounting or attachment.

It is another object to provide an improved abutment means for a resilient flight mounting.

It is a further object to provide an improved resilient suspension in a resilient flight mounting.

It is a general object to meet the above objects with a structure that is simple and relatively cheap to manufacture and which, at the same time, is adequately rugged and easy to service.

Other objects and various further features of the invention will be pointed out or will occur to those skilled in the art from a reading of the following specification in conjunction with the accompanying drawings. In said drawings, which show, for illustrative purposes only, a preferred form of the invention:

Fig. 1 is a fragmentary view, partly in section and showing a conveyor carrying a resilient flight mounting that incorporates features of the invention;

Fig. 2 is a view in section more or less in the plane of the lines 2—2 of Fig 1; and

Fig. 3 is a fragmentary sectional view more or less in the plane 3—3 of Fig. 2.

Briefly stated, my invention contemplates a resilient flight mounting, wherein resilient forces may be more or less tangentially applied to one of two relatively rotatable flight-mounting members, more or less regardless of the stress to which said resilient means is subjected. The resilient means may be a straight coil spring guided by one of the members and engageable with abutment means on the other member. In the preferred form shown, the spring may be insertably removed out the open end of the guide means when the flight is removed; when the flight is attached, the flight itself provides the necessary abutment for the other end of the spring.

2

Referring to the drawings, my invention is shown in application to a conveyor having a side chain 5, which may be one of two conveyor side chains supported in spaced relation within a self-loading refuse truck. At spaced intervals along and between such side chains there may be supported flights, such as the flight 6, for the conveyance of refuse into the body of the truck. Each chain of the conveyor 5 may include links such as the link 7 between spaced pivotal connections 8. Rollers 9 may be supported at each pivot location.

In accordance with the invention, I provide novel resilient mounting means for the flight 6 and carried by the conveyor chain 5, and it will be understood that a similar mounting means may be carried by the other side chain (not shown) for supporting the other side of the flight 6. The mounting may comprise two relatively rotatable members 10—11 in mutual supporting relation, and both members 10—11 may be supported on the extended shank 12 of one of the pivot pins 13 between chain links. The members 10—11 may define a space between them; and in the form shown such space is annular, as by forming the member 11 essentially as a disc, and the member 10 as an annular cup fitting the disc 11. Both members 10—11 may include boss or bearing portions 14—15, respectively, which interfit for relatively rotatable support of members 10—11, and, if desired, a wear bushing 16 may be inserted between the boss portions 14—15. In order to anchor the plate or disc member 11 to the conveyor, a stud 17 with a rivet head may be carried thereby for riveted engagement with the link 7, as shown in Fig. 1. A securing nut 18 may be threaded to the projecting shank 12 of the pivot pin 13 in order to secure the relatively rotatable members 10—11 to each other and to the conveyor; and a cover disc 19 may be seated against the bottom of a counterbore in the cup member 10 and held therein, as by a snap ring 20, in order to seal off one side of the flight-mounting assembly. If desired, felt or other seal means 21 may be held in an annular groove in the periphery of the disc member 11 for continuous engagement with the inner surface of the cup member 10, in order to seal off the other side of the assembly. If desired, the nut 18 may be a so-called castle nut, so that a cotter pin (not shown) may hold the nut 18 against loosening.

In order to limit relative angular movement of the two flight-mounting members 10—11, I provide spaced abutment means on these members. In the form shown, such abutment means

comprises spaced webs 22-23 which may be formed integrally with the cup member 10 and extend generally radially between the boss 14 and the outer skirt of the cup member 10. A fixed abutment 24 on the disc member 11 may project into the annular space between members 10-11 and between the abutments 22-23.

For the forms shown, I employ single-acting resilient means to urge the flight abutment 22 normally against the conveyor abutment 24. Such spring means may resiliently absorb flight loads tending angularly to displace the abutments 22-24 apart, but the abutment means 23 will be understood to limit the extent of such displacement. The resilient means may be a single coil spring 25 reacting between the two relatively rotatable members and, in the form shown, the spring 25 is guidably supported within a passage 26 in the cup member 10. The passage 26 may communicate with the annular open space within the cup so as to provide a means of resilient abutment with a second fixed abutment member 27 carried by the disc member 11. To improve the action of resilient abutment, I prefer to employ a generally hollow guide member or nose 28 to be slidably guided by the passage 26 and to locate and receive the spring 25. The abutment end of the member 28 may directly engage the abutment 27, and one or the other or both these members may be formed with a rounded abutment edge, as at 30, in order to promote a good abutment for any angular relationship of the relatively rotatable members 10-11.

The passage 26 which slidably guides the resilient means 25-28 may be extensive to such an extent that it may be open at the outer end of the flight-mounting arm 31, to which the flight is secured. When secured in this manner, it will be understood that the spring 26 may be suitably preloaded as the securing bolts 32 are tightened.

It will be appreciated that I have described a relatively simple resilient flight mounting. The parts of my mounting may be extremely rugged and readily accessible for servicing. All moving parts may be adequately sealed against the entrance of foreign matter, and yet the spring means 25 may be easily removed and replaced merely by dislodging the flight 6. When so dislodged, the reaction point for the spring 25 will have been removed so that no parts will be stressed. Conversely, in assembling my flight mounting there is no danger to personnel due to any necessity for preloading the spring means during assembly, for the preloading is accomplished after all flight-mounting parts have been assembled and during a final take-up of the securing bolts 32.

While I have described my invention in detail for the preferred form shown, it will be understood that modifications may be made within the scope of the invention as defined in the appended claims.

I claim:

1. In a flight mounting, a pair of relatively rotatable members rotatably secured together,

one of said members including means for attachment to a conveyor and the other of said members including means for detachably supporting a flight, abutment means on said one member, longitudinally displaceable spring means carried by said other member and engageable with said abutment, one end of said spring means being disposed for operative supporting engagement with a flight supported by said other member.

2. In a flight mounting, a pair of relatively rotatable members rotatably secured together and defining an enclosed space between them, an abutment on one of said members and projecting into said space, the other of said members having a guide opening extending more or less tangentially into said enclosed space, spring means guided in said opening and projecting into said space for engagement with said abutment means, and a flight member disposed so as to close one end of said guide opening in abutting relation with one end of said spring means.

3. In a flight mounting, a pair of relatively rotatable members defining an enclosed space between them and rotatably supporting each other, abutment means on said one member and projecting in said space, one of said members including means to be engaged by a conveyor element, the other of said members including means to engage a flight, said other member having a guide passage communicating between said flight and said space for accommodation of a spring to abut said abutment means at one end and to abut the flight at the other end.

4. In a flight mounting, a pair of mutually supporting relatively rotatable members defining an enclosed generally annular space between them, one of said members having a first abutment off the rotatable axis thereof and extending into said space, said one member including means to be engaged by a conveyor element, the other of said members having a generally radially extending arm for attachment to a flight and said arm having a passage open at one end more or less tangentially into said space and open to the outside at the other end, spring means including second abutment means adapted to be guided by said passage for engagement with said first abutment means and with a flight secured to the end of said arm.

ERNEST C. C. MILLER.
